UNITED STATES PATENT OFFICE.

JOHN A. CRAWFORD, OF ALLEGHENY, PENNSYLVANIA.

SMOKE-CONSUMING FURNACE.

SPECIFICATION forming part of Letters Patent No. 658,703, dated September 25, 1900,

Application filed November 4, 1899. Serial No. 735,786. (No model.)

To all whom it may concern:

Be it known that I, JOHN A. CRAWFORD, a citizen of the United States, residing at Allegheny, in the county of Allegheny and State 5 of Pennsylvania, have invented certain new and useful Improvements in Smoke-Consuming Furnaces; and I do hereby declare the following to be a full, clear, and exact description of the invention, such as will enable others skilled in the art to which it appertains to 10 make and use the same.

My invention has relation to smoke-consuming furnaces; and the objects are, first, to provide a smoke-consuming furnace which 15 is simplified in construction, efficient in operation, and durable in use; second, to provide such a furnace which presents an improved preservative construction, whereby the respective elements are prevented from 20 being destroyed by the caloric effects of the burning gases and flames, and, third, to provide improved means for regulating the drafts to the air-pipes opening from the ash-pit.

With these purposes or objects in view my 25 invention consists in the novel construction of parts and their combination, as will hereinafter be fully described, and particularly and distinctly pointed out in the claims.

I have fully and clearly illustrated my improvements in the accompanying drawings, 30 wherein—

Figure 1 is a vertical section longitudinally through the furnace and inner face of one of the side walls thereof, showing air-intake flues leading from the ash-pit, the gas-flues 35 leading from the fire-chamber, and the air and gas pipes opening above into the fire-chamber, also showing the air-intake and gas and air discharge pipe. Fig. 2 is a vertical transverse section through the side wall, 40 showing the gas channel or chamber, the figure being taken on the line 2 2 of Fig. 1. Fig. 3 is a vertical transverse section taken centrally through the draft-box and vertical 45 flue, as indicated by the line 3 3 of Fig. 1. Fig. 4 is a horizontal section on the line 4 4 of Fig. 1. Fig. 5 is a detail central longitudinal section through one of the draft-boxes, 50 showing the rod to operate the draft slides or damper. Fig. 6 is a similar view to Fig. 5, taken at cross-section thereto.

Referring to the drawings, A A designate the side walls of the furnace; B, the front wall; C, the grate-bars, and D the bridge-wall.

In the side walls of the furnace leading 55 from the ash-pit E into the side walls are formed air-flues 7, leading into the walls at right angles and then vertically in the walls, as shown in Fig. 3 at 8 and indicated in dotted lines in Fig. 1, and opening at their 60 upper open ends into a horizontal gas channel or chamber 9, extending longitudinally in the walls on a plane above the grate-bars, as shown, and leading into this gas channel or chamber are a plurality of oblong narrow 65 flues 10, opening from the fire-chamber into the gas-channel 9, as shown in the drawings.

In the longitudinal portions of the air-intake flues 7 are arranged and fitted metal boxes F, the bodies of which are of a contour 70 to slide into and fit the front portion of the flues and about their outer edges are formed with grooved flanges 11, in which is slidingly fitted a plate-damper 12, arranged to close the opening 13, leading into the boxes or 75 sleeves F. The opening 13 is preferably smaller in area than the area of the flues and bodies of the boxes. The flues 7 are arranged intermediate of the flues 10 in order that the draft from flues 7 will intersect the gas-channel 80 remote from the flues 10, and the upper gas and air pipes, when the latter are used, will be remote or a sufficient distance to remove them from the direct action of the hot 85 flames and gases when the air and gas pipes or flues are used or brought into requisition.

It will be perceived that, so far as the invention has been described, a complete and effective combustion and smoke consumer is afforded. The air being taken from the ash- 90 pit and delivered to the fire-chamber promotes combustion in the latter to effectually eliminate the smoke by enhanced caloric effects.

Suitably seated in the walls, with their 95 lower ends opening into the gas-channel and registering with the vertical portions or branches of the flue 7, are air and gas pipes G, extending vertically, as shown in dotted lines, and formed with downwardly-inclined 100 ends g, opening through the face of the wall into the fire-chamber above the gas-channel

flues. When these gas and air pipes are used, the operation is as follows: The air from the ash-pit is taken up through the air-intake flues therein and is carried up into the air 5 and gas flues. At the same time a side draft is created from the fire-chamber through the flues into the gas-channel, the gases being led in the channel into the gas and air pipes into the fire-chamber to promote combustion and 10 consume the smoke.

In the bridge-wall is formed a gas-channel 14, which at the ends is in communication with the gas-channels in the side walls, and leading into this gas-channel 14 are flues 15, 15 opening from the fire-chamber, and opening from the ash-pit are air-flues 16, which intersect the bridge-wall gas-channel by means of vertical branches 16, as shown in the drawings. At the upper end of these air-flues in 20 the bridge-wall over the gas-channels are placed gas and air pipes 17, similar in construction to the pipes in the side walls, and seated with their bases substantially on a line with the gas-channels and their inclined 25 upper ends directed forward and opening into the fire-chamber at the front of the bridge-wall, the object being to provide additional means for promoting combustion in the fire-chamber. The entrance or flow of air into 30 the flues in the bridge-wall is regulated by means identical to those used for regulating the draft in the flues and pipes in the side walls.

It will be perceived that in the construction and arrangement of the elements of 35 my improvement or invention I have provided a device which may be effectively used without or with steam jets to promote the draft and delivery of the gases and air to the 40 fire-chamber. If steam-jets are desired, they

can be readily and conveniently applied in any manner within the skill of the mechanic.

What I claim is—

1. In a smoke-consuming furnace the combination of the side walls formed with longitudinal gas-channels located above the grate-bars, gas-flues leading from the fire-chamber and intersecting the gas-channels, and air-flues opening from the ash-pit and intersecting the gas-channels intermediate of the gas-flues, air and gas pipes placed above the gas-channels and opening at their base into the gas-channels and registering with the upper ends of the air-flues, and formed with downwardly-inclined branches opening into the 55 fire-chamber, metal boxes in the mouths of the air-flues in the ash-pit, and slides to adjustably close the mouths of the metal boxes, substantially as described.

2. The combination with the side walls 60 formed with longitudinal gas-channels and gas-flues opening therein from the fire-chamber, of the bridge-wall formed with a gas-channel communicating at its ends with the gas-channels in the side walls, gas-flues in the 65 bridge-wall opening from the fire-chamber and intersecting the gas-channel, air-flues opening into the bridge-wall from the ash-pit and intersecting the gas-channel in the bridge-wall, air and gas pipes in the bridge-wall having their bases opening into the gas-channel therein and formed with downwardly-inclined and forwardly-directed ends opening into the fire-chamber, substantially as described.

In testimony whereof I affix my signature 75 in presence of two witnesses.

JOHN A. CRAWFORD.
